UNITED STATES PATENT OFFICE.

MERRITT H. DEMENT, OF NEW YORK, N. Y.

TYPE WRITING AND PRINTING MACHINE.

SPECIFICATION forming part of Letters Patent No. 282,175, dated July 31, 1883.

Application filed January 11, 1882. (No model.)

To all whom it may concern:

Be it known that I, MERRITT H. DEMENT, a citizen of the United States, residing at New York, in the county of New York and State of New York, have invented certain new and useful Improvements in Type Writing and Printing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to the arts of type writing and printing; and it consists of the devices and combinations as hereinafter described, and specifically pointed out in the claims.

20 In the accompanying drawings, Figure 1 is an end view of the machine. Fig. 2 is a side view of the same, showing cylinder with rods running longitudinally in it, type-wheel, and end of shaft. Figs. 7 and 8 are different views 25 of one of the rod ends. Fig. 3 is a view of a portion of one of the type-rings with groove. Fig. 4 is a tongued ring to fit groove in Fig. 3. Fig. 5 is a side elevation of a type, showing groove. Fig. 6 is a cross-view of a segment of the ring in Fig. 4, showing tongue. I do not, in this application, claim anything in 30 reference to either of the Figs. 3, 4, 5, or 6, nor in reference to the construction of the type-rings. Fig. 9 is a view of the end of a rod passing the bevel which crowds the rod back into 35 the cylinder after printing.

40 My machine consists of a revolving cylinder with any desired number of longitudinal grooves, in which are placed bars or rods capable of sliding in the grooves the desired distance. The rods are caused to slide by means of a key-board. The key is depressed and the opposite end of the key-bar is pressed against the cylinder. The key-bar being provided 45 with a beveled head and the cylinder-rod being provided with a beveled pin or head, when the two come in contact by the revolution of the cylinder, the result is that the rod is slid or forced along in its groove, so as to protrude 50 from the end of the cylinder. At the end of the cylinder, and on the same shaft concentric

with it, is the type-wheel, as shown in Fig. 2, it being of a smaller diameter, so that the rod ends, when slid out, will extend over the type. This wheel may be composed of a number of rings, each ring containing a row of type, the whole being made to be moved longitudinally upon the shaft, so as to bring any desired row of type in position. Each key in the key-board connects with and pushes out a particular rod; and that rod, when pushed out, will protrude from the cylinder and be directly over the particular type belonging to the key that is operated upon. A strip of paper (represented by the line G, Fig. 1) passes or lies 65 immediately between the rod end when pushed out and the type. The objects to be accomplished are to press the rod end on the paper strip, thus forcing the strip on the type and making the print or indentation; to gage the 70 length of time the paper is thus held, so as to give each letter its proper space by the type and rod end so pressing the paper between them as to pull it along; to relieve the pressure instantly by a positive action, and to return 75 the rod into the cylinder. To accomplish the first result, I provide a suitable bevel, (shown as H in Figs. 1 and 2,) along which the protruding rod end passes, and by which it is 80 pressed on the paper. In order that each letter may have its proper space, I cause the rod ends to be made of varying thicknesses at a point near the end, (shown in Fig. 7 by Z,) according to the width of the type on which it 85 operates. The point Z, Fig. 7, being the portion of the rod end which passes along the bevel H, it will be seen that the wider the rod end is made at Z the longer the rod end will 90 be in passing the highest point of the bevel H. The rod is widened, as shown in Fig. 7, 95 by adding the extra width on what may be called the "forward" side of the rod as it revolves, so that the rear side is plain. The paper having been pressed on the type and retained there the proper time to give each letter its proper space, it becomes necessary to relieve the pressure and release the paper. This I accomplish the instant the rod end (a in Fig. 2, and Z, Fig. 7) shall have passed the highest point of the bevel H, Figs. 1 and 2, 100 by providing a bevel so placed that the end of the rod y, Figs. 7 and 8, will strike and

pass along it, and the rod thus instantly be lifted from the paper, the plate N being a guard to hold it from going too far. To return the rod end to the cylinder, I provide and 5 place immediately after the last bevel another bevel, as shown in Fig. 9, which operates directly on the end of the rod, and as the rod end passes along it the rod is forced back to its position in the cylinder.

- 10 For the purpose of making or leaving blank spaces on the strip, such as occur between words, I place on the type-wheel, in the proper position to be operated upon by the rod connecting with the spacing-key, a blank type or 15 pin with a flat or slightly convex head, having nearly or quite the same periphery as the type-heads. This may, if necessary, be slightly milled or roughened. Then I place on the inner side of the rod end, at the point Z, one or 20 more small pins or points, the rod at Z having the width to give the desired space. The paper is pulled the desired distance by being caught between the blank type and the rod end, the small pins or points on the latter 25 holding it securely until the paper is released, as in the process of printing a letter, as above described.

It will be seen that in case several rows of type are used it may be necessary to provide 30 the rods with other widened spaces at Z, if the different type coming under any rod should require different spacing. In such case the bevel-plate H should be made movable. With this mode of depressing the rod end by means 35 of a stationary bevel and giving each letter its proper space by means of making the rod ends of various widths at the point Z, thus avoiding the necessity of using a large spacing-wheel and of relieving the paper by a 40 positive bevel action, so that when operated rapidly the paper will not be pulled too far the machine is capable of being operated at a larger number of revolutions per minute than by any other known mode of performing such 45 actions. This enables me, even if I run my machine at the same number of revolutions made by other machines, to enlarge my type-wheel so as to accommodate on one row two full alphabets of type—that is, one of capitals and one of small letters—besides ordinary 50 punctuation and other marks, even including numerals, if necessary, and thus make it unnecessary to shift from one row to another, as is now done at a great inconvenience and loss 55 of time.

The process of printing by my machine is accomplished with marvelous rapidity, the cylinder being capable of making from three hundred to four hundred revolutions per minute, and printing at each revolution one or more or even all the letters on the type ring.

By turning the screws M M, Fig. 1, the bevel-plate H may be raised or depressed to regulate the depth of the indentations made 60 in the paper.

I also make an improvement in the method of holding the type rigidly in place in the type-

ring, and at the same time making them readily removable. I accomplish the first result by making a groove around the side of the 70 type-ring and in the types themselves, as shown in Fig. 3, and making a companion ring with a tongue to correspond with the groove, as shown in Fig. 4, and placing the two rings together, the tongue fitting in the groove, 75 thus firmly holding the type in place. The type are made removable with ease by making the type-ring of two semicircles, which, when put together on the shaft, form a ring, the ends being clasped and held together by 80 means of clasp-springs, or a hinge and spring, similar to the manner of clasping ladies' bracelets. To more readily fix the location of each type exactly under the proper rod end, and to keep the type-ring from revolving on the shaft, 85 I make tongues in the shaft, as shown in Fig. 3, which fit in corresponding grooves in the ring. Joints are also to be made in the rods at a convenient distance from the ends, so that 90 the ends may be readily removed in case of injury or change of type, and others substituted.

One very important feature about my machine, thus constituted, is that it can be readily changed, so that, instead of making type-matrices, it will print type forms or letters, in 95 ink, on a strip of paper. This is accomplished by depressing the bevel-plate H by means of the screws M M, as above described, and adding a suitable inking apparatus. For the 100 purpose of providing a proper spacing mechanism for this process, I mill the periphery of the ring shown in Fig. 4, or place a suitable milled ring in the proper place on the type-wheel, with the proper periphery, which will 105 perform the function, with the aid of the rod end, of grasping the paper and causing it to space, which is performed in the other process by the type.

I am aware that there is now in use a machine 110 having a cylinder and sliding rods in combination with a cam resting upon a spring, the rod, when operating, passing under a fixed plate, which presses the spring down until the rod reaches the printing point, when the rod 115 is released, and the spring operates to throw it upward on the type.

I am aware, also, that a cylinder and sliding rods have been used in combination with a pawl operating in connection with a ratchet 120 wheel, the rod, when operating, striking the under side of the pawl, and causing it to engage with a ratchet in the wheel, which, in turn, drives the pawl back on the rod and the rod down on the paper and type.

Certain devices herein shown, but not specifically claimed, are claimed in other applications by me now pending in the Patent Office, or will be claimed in applications to be hereafter filed.

Having thus fully described my invention, what I claim as new, and desire to secure by Letters Patent, is—

1. The combination of a cylinder, a series

of sliding rods, and with a rigid stationary cam, by means of which the rods are pressed upon the material operated upon, substantially as shown and described.

5 2. In a type writing or matrix machine, the combination of a series of rods in a revolving holder and a vertically-adjustable cam for pressing the rods upon the material operated upon.

In testimony whereof I affix my signature in presence of two witnesses.

MERRITT H. DEMENT.
